UNITED STATES PATENT OFFICE.

JOHN B. KUNKEL, OF PHILADELPHIA, PENNSYLVANIA, ASSIGNOR TO HALE AND KILBURN, OF PHILADELPHIA, PENNSYLVANIA, A CORPORATION OF DELAWARE.

STATIONARY SEAT FOR CARS AND OMNIBUSES.

1,231,914.

Specification of Letters Patent.

Patented July 3, 1917.

Application filed August 21, 1915. Serial No. 46,591.

To all whom it may concern:

Be it known that I, JOHN B. KUNKEL, a citizen of the United States, residing at Philadelphia, in the county of Philadelphia and State of Pennsylvania, have invented 5 certain new and useful Improvements in Stationary Seats for Cars and Omnibuses, of which the following is a specification.

My invention relates to a stationary seat 10 having a frame preferably composed of pressed metal members and having the advantages of lightness, rigidity, cheapness and simplicity of manufacture and assembling. The construction is designed chiefly 15 for use in the so-called "jitney" or other omnibuses, but it is equally applicable for use in railway and other cars in which stationary seats are desirable. Briefly, the construction may be described as comprising a 20 frame having end supports for the seat, vertical end members for the back rising from the rear of the seat supports and a transverse top member extending between the upwardly extending back standards. The end- 25 seat supports are formed with inwardly directed top and bottom flanges and front flanges extending lengthwise of the seat. The back standards are formed with rearwardly directed webs, front flanges extending 30 lengthwise of the back and a stiffening bead along the rear and bottom edges of the web. A channel-shaped front rail is mounted 35 within the front flanges of the seat supports and an angular bar connects the seat supports at the rear. The seat-cushion rests 40 on the top flanges of the seat frame thus formed. A metal sheet is secured to the front flanges of the back standards, extending upwardly only for a part of the height 45 of the standards, this sheet being curved forwardly at its lower end to be secured to the top rear flanges of the seat frame. A trans- 50 verse stiffening member is secured to the upper edge of the back-sheet referred to and to the front flanges of the back standards, and the back-cushion is mounted against the 55 front flanges of the back standards to bridge the space between the upper edge of the back-sheet referred to and the top cross-member of the back.

In order that a clearer understanding of my invention may be had, attention is hereby directed to the accompanying drawings forming part of this application and illustrating certain embodiments thereof. In

the drawings, Figure 1 represents an end elevation of my improved seat mounted upon suitable supports, Fig. 2 is a vertical section through my improved construction taken on line 2-2 of Fig. 3 and Fig. 3 is a front elevation of the construction.

Referring to the drawings a pair of end-seat supports 1, 1 are employed from the rear ends of which rise the back standards 2, 2 which are connected at their upper ends 65 by the transverse member 3. Preferably, as stated, the seat supports 1 are formed with inwardly directed bottom and top flanges 4 and 5 respectively, which flanges are connected by the front flanges 6 extending inwardly, lengthwise of the seat, from the webs of the members. The back standards 2 are formed at their lower ends with offset portions 7 joining the rear ends of the seat supports when, as in the form illustrated, the seat is of a greater length than the back. The back standards are formed of pressed metal having front flanges 8 extending inwardly, that is lengthwise of the seat, from the web portions 9 which extend 70 rearwardly in vertical planes. At the rear of each web portion, the latter is beaded or curved inwardly as shown at 10, to form a rigid construction, this beading extending along the bottom forwardly curved edge of 75 each web portion of a back standard. The top transverse member 3 is provided at its rear edge with a similar beading, from which the member extends horizontally to the front and thence is flanged downwardly 80 at an angle as shown at 11. The seat and back frame thus provided may be formed as an integral construction as illustrated, bent and pressed to shape, or it may be formed of separate members, welded or 85 otherwise suitably secured together.

A front rail 12 is secured within the front and bottom flanges of the end supports 1, this front rail preferably taking the form of a channel-bar having rearwardly directed top and bottom flanges. The seat supports 1 are connected at the rear by a transverse angular member 13 preferably in the form of a Z-bar, the bottom flanges of which are secured to the bottom flanges 4 100 of the seat supports, the top flanges of the bar extending rearwardly. The seat frame is reinforced by suitable means, preferably by an angle-bar 14 extending from front to back at an inclination and secured at its 105 110

ends upon the bottom flanges of the front and back rails 12 and 13.

The seat-cushion 15 is mounted upon the top flanges of the seat frame described. This cushion comprises a metal sheet 16 upon which is mounted felt or other upholstery material 17 covered by ratan or other suitable upholstery 18. A number of suitable reinforcing members 19 are secured 10 to the under side of sheet 17 and extend from front to rear of the same. These preferably take the form of channel-bars as shown. The seat may be secured in position by screws or other suitable securing means 15 20, 21, extending through the top flanges of transverse members 13 and 12 respectively and the rear and front edges of sheet 16, the ratan or covering 18 being bent around the cushion frame at the edges and secured by 20 screws 20, 21 between the top flanges of members 13 and 12 and sheet 16. The reinforcing channels 19 are preferably secured at their ends by the same screws 20 and 21.

A metal back sheet 22 is secured between 25 the front flanges 8 of the back standards, this sheet preferably extending upwardly for only a part of the height of the back standards. Sheet 22 at its lower end is curved forwardly as shown at 23, its lower 30 edge being secured within the top flange of the rear cross-bar 13, by screws 20. A transverse stiffening bar 24 is secured to the upper edge of back-sheet 22 and to the flanges 8 of back standards 2. Member 35 24 preferably takes the form of a channeled or rearwardly curved member having top and bottom vertical flanges. The back-cushion 25 is secured in position across the front flanges 8 of back standards 2, between 40 the top of back-sheet 22 and the forward flange 11 of the top member 3 of the back-frame. The back-cushion preferably consists of a metal sheet 26 having a covering of felt or other suitable material 27 over 45 the same, which is covered or held in place by an outer layer 28 of ratan or other suitable material. The ratan is bent around the edges of the back-cushion frame as illustrated, strips 29 being interposed at the top 50 and bottom edges of the cushion. The cushion may be held in place by screws 30, 31 at the bottom and top edges of the cushion which extend respectively through sheet 22, the lower flange of member 24, the 55 lower edge of the ratan and the lower strip 29, and through flange 11 of top member 3, sheet 26, the upper edge of the ratan, and the upper strip 29. The upper flange of stiffening member 24 rests against and 60 may be secured to the rear surface of sheet 26. The seat may be supported by suitable means such as the cricket 32 at the aisle end and the wall-bracket 33 at the wall end by bolts 34 extending through the bottom 65 flanges of the seat supports 1.

It will be obvious from the above description that my improved seat is light and strong, may be efficiently manufactured of standardized parts economically and may be assembled or taken apart with slight expenditure of labor. 70

Having now described my invention, what I claim as new therein and desire to secure by Letters Patent is as follows:

1. In a stationary seat, the combination 75 of a pair of end-seat-supports and members extending upwardly from the rear of said supports, said supports being horizontally flanged at top and bottom and said upwardly-extending members having rearwardly extending vertical webs with front flanges transverse to the webs, a transverse angular bar having its bottom flanges secured to the bottom flanges of said supports, a metal back-sheet having a horizontal offset portion at its lower end secured to the top flanges of said bar and an upwardly extending portion secured to the front flanges of said upwardly extending members, and a seat cushion secured on the top 80 flanges of said supports and transverse angular bar, substantially as set forth. 85

2. In a stationary seat, the combination of 90 a pair of end seat-supports and members extending upwardly from the rear of said supports, said supports being horizontally flanged at top and bottom and said upwardly extending members having rearwardly extending vertical webs with front flanges transverse to the webs, a metal back-sheet having a lower portion secured to flanges of said supports and an upwardly extending portion secured to the front flanges of said upwardly extending members, said back-sheet being of less height 95 than said upwardly-extending members, a seat secured on the top flanges of said supports, and a back-cushion secured to said upwardly extending members, between the 100 upper portion of said back-sheet and the top of said upwardly extending members, substantially as set forth. 105

3. In a stationary seat, the combination 115 of a seat frame, a back frame rising from the rear thereof, comprising standards having rearwardly extending webs and front flanges, a metal sheet secured to said seat frame and front flanges, of less height than said standards, a transverse stiffening member secured to the upper edge of said sheet and to said front flanges, and a back-cushion secured across said front flanges, to said stiffening member and the upper edge of said sheet, substantially as set forth. 120

4. In a stationary seat, the combination of 125 a seat-frame, a back-frame rising from the rear thereof, comprising standards having webs and front flanges, a transverse top member between said standards, having a 130

front flange, a metal sheet secured to said seat frame and to the front flanges of the standards, of less height than said standards, a transverse flanged stiffening member secured to the upper edge of said sheet and to the front flanges of the standards, and a back-cushion secured across said front flanges of the standards, said cushion being secured at the bottom to said stiffening member and the upper edge of said sheet, and at the top to the front flange of said transverse top member, substantially as set forth.

5. In a stationary seat, the combination of a pair of end-seat supports and standards extending upwardly from the rear thereof, said supports having horizontal flanges at top and bottom, a front rail secured within the flanges of said supports, a

rear transverse member of Z-shape, having 20 its forwardly directed bottom flange secured to the bottom flanges of said supports, a metal back-sheet secured to said standards and having a forwardly directed bottom portion lying against the top flange of said 25 rear transverse member, and a seat-cushion on the top flanges of said supports and secured to said front rail at the front and to the bottom portion of said back-sheet and the top flange of said rear transverse member at the rear, substantially as set forth. 30

This specification signed and witnessed this 19th day of August, 1915.

JOHN B. KUNKEL.

Copies of this patent may be obtained for five cents each, by addressing the "Commissioner of Patents, Washington, D. C."

It is hereby certified that the assignee in Letters Patent No. 1,231,914, granted July 3, 1917, upon the application of John B. Kunkel, of Philadelphia, Pennsylvania, for an improvement in "Stationary Seats for Cars and Omnibuses," was erroneously described and specified as "Hale and Kilburn," whereas said assignee should have been described and specified as *Hale and Kilburn Company*, as shown by the records of assignments in this office; and that the said Letters Patent should be read with this correction therein that the same may conform to the record of the case in the Patent Office.

Signed and sealed this 14th day of August, A. D., 1917.

[SEAL.]

R. F. WHITEHEAD,

Acting Commissioner of Patents.
